Inventor:
Rudr Stockinger
say
George Young
Attorney

UNITED STATES PATENT OFFICE.

RUDE STOCKINGER, OF MANITOWOC, WISCONSIN.

ELECTRIC VIBRATOR.

1,270,342.

Specification of Letters Patent. Patented June 25, 1918.

Application filed August 7, 1917. Serial No. 184,872.

To all whom it may concern:

Be it known that I, RUDE STOCKINGER, a citizen of the United States, and resident or Manitowoc, in the county of Manitowoc and State of Wisconsin, have invented certain new and useful Improvements in Electric Vibrators; and I do hereby declare that the following is a full, clear, and exact description thereof.

0 My invention relates to certain new and useful improvements in vibrating devices of that type exemplified in an application filed by me May 3, 1917, Serial No. 166,107.

In most devices of this character now in general use, the coil becomes heated when in continuous use for any length of time and thus consuming an excessive amount of energy in order to provide the successful operation of the device. With this inherent objection in view, my invention has for its primary object to reduce this heating of the magnetic coil to a minimum whereby to provide a vibrator which will be economical in its consumption of electrical energy.

25 A further object resides in bending laterally certain of the laminæ of the core of my device whereby the same is resiliently supported over its base.

With the above and other objects in view 30 which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings I have 40 illustrated one complete example of the physical embodiment of my invention constructed according to the best mode I have so far devised for the practical application of the principles thereof, in which:

45 The single view is a side view of my invention with parts broken away and in section to more clearly illustrate structural details.

Referring now more particularly to the 50 accompanying drawings, 5 designates a

laminated core having certain of its laminæ bent laterally as at 6 having their outer ends secured as at 7 to the outer ends of a pair of non-magnetic supporting members 8 having their inner ends secured to a magnetic base 55 plate to be later described. A spool 9 surrounds the core 5 and has mounted thereon the usual magnet windings 10 and adapted when energized to procure vibratory movement of the magnetic body to thus exert a 60 series of taps upon the supporting base.

The most important feature of the present invention is in forming the supporting base plate 11 of laminæ running in parallel to the laminæ of the core and secured together 65 by means of a rivet or bolt 12, a suitable work engaging lug 13 being secured to the base 11 in any desired position or manner.

As hereinbefore mentioned, the constructing of the base plate 11 with laminations 70 running in parallel with the laminations of the core or armature 5, the coil or magnet windings 10 does not overheat as is generally the case.

From the foregoing description taken in 75 connection with the drawings, it will be readily understood that upon the passage of successive electric impulses through the electro-magnet, the core or armature 5 with the magnetic windings surrounding the same, 80 will vibrate rapidly and thus exert a series of taps upon the base 11 as will be obvious to those skilled in the art to which an invention of this character appertains.

I claim:

1. A vibrator comprising a magnetic base plate composed of laminæ secured together by a binding rivet, spaced non-magnetic supporting members having their inner ends fixed to the base plate, a laminated core having certain of its laminæ bent laterally and secured to said supporting members, whereby the core is resiliently supported between the supports, and magnet windings surrounding the core, substantially as described. 90

2. A device of the type described comprising, in combination, a laminated magnetic base plate, non-magnetic supporting members having their inner ends fixed to the base plate, a laminated core disposed inter- 100

mediate the supporting members, means projecting laterally from said core for secure-
ment to said supporting members, whereby
the core is resiliently held from engagement
with the base plate, and magnetic windings
surrounding the core and adapted to cause
the core to assert a series of taps upon the

base when energized, substantially as de-
scribed.

In testimony that I claim the foregoing 10
I have hereunto set my hand at Manitowoc,
in the county of Manitowoc and State of
Wisconsin.

RUDE STOCKINGER.
